UNITED STATES PATENT OFFICE.

HENRY R. PLIMPTON, OF BOSTON, MASSACHUSETTS.

SOFA OR LOUNGE BED.

SPECIFICATION forming part of Letters Patent No. 247,683, dated September 27, 1881.

Application filed April 7, 1880. (No model.)

To all whom it may concern:

Be it known that I, HENRY R. PLIMPTON, of Boston, in the county of Suffolk and State of Massachusetts, have invented a new and 5 useful Attachment for Sofa or Lounge Beds, &c., of which the following is a specification.

My invention consists in the combination, with the back and base of a sofa or lounge bed, of re-entering toggles, flexible spring-plates, 10 and a cord, operating together, substantially in the manner as will be hereinafter more fully set forth in the specification, and pointed out in the claim.

In the drawings, Figure 1 is an end elevation, showing my device as applied to a sofa or lounge bed. Fig. 2 is a rear elevation of the same. Fig. 3 shows, in detail, a thin metallic plate, one end of which is to be made fast to the back of the sofa or lounge, while one 20 corner of the other end is turned up, so that a cord or chain attached to it may, when pulled, serve to turn it partly on edge, and thus pry away the center of the toggle, as shown in Fig. 4. Fig. 4 shows the central part of one of the 25 toggles and a section of the metallic plate for throwing out the central joint of the toggle, and thus allowing the back to be turned down.

A and B represent the base and back of a sofa or lounge bed. To the base I pivot a link, 30 D', at C', and to the back I pivot a link, D, at C, the two links D and D' being pivoted together at M, so as to form a toggle when the back is up, as shown in Figs. 1 and 2. This pivot M passes beyond the line which connects C and C', (see Fig. 1,) so that pressure 35 on the back of the sofa or lounge will cause the center of the toggle to press against the back, or in the direction indicated by the arrow at T, Fig. 1. Thus the toggle device, which 40 in the dotted lines of Fig. 1 is a leg and leg-

brace, now becomes a firm brace for keeping the back of the sofa in an elevated position, and requires no fastening device.

When it is desired to turn the back down the center M of the toggle must be thrown out 45 beyond the line of centers C C'. In order to do this with facility I have placed the flat flexible spring-metal plate H on the back, as shown, one end being securely fastened by the screws S S, while the other end, K, is loose. The 50 cord L is attached to a turned-up corner, k, of this plate, as shown in Figs. 2 and 3. Now, as this plate H K underlies the toggle, it is evident that if the cord L is pulled it will twist the lower edge of the plate upward and outward, and thus force the toggle away from the back, as shown in Fig. 4. This will throw the joint outside of the line of centers, and then the toggle will be free to bend outward, and thus allow the back of the sofa or lounge to be 55 turned down.

I do not claim the toggles as such, nor in combination with the back of a sofa or lounge.

My invention consists in so locating the center or pivot upon which the links of the toggle turn that when the back is up the toggles 60 become re-entering and self-supporting.

Having thus described my invention, what I desire to secure by Letters Patent is—

In a sofa or lounge bed, the combination of 70 the back B, base A, and the re-entering toggle D D' with the flexible spring-plate H K and cord L, all operating together substantially as described, and for the purpose set forth.

HENRY RICHARDSON PLIMPTON.
